UNITED STATES PATENT OFFICE.

JOHN A. THAKE, OF BROOKLYN, NEW YORK.

RENEWABLE-LINK ELECTRIC FUSE.

1,319,538.

Specification of Letters Patent.

Patented Oct. 21, 1919.

Application filed May 17, 1918. Serial No. 235,150.

To all whom it may concern:

Be it known that I, JOHN A. THAKE, a citizen of the United States, and a resident of the borough of Brooklyn, in the city and State of New York, have invented certain new and useful Improvements in Renewable-Link Electric Fuses, of which the following is a specification.

This invention is intended, primarily, for so-called plug fuses, in which the fusible link is mounted in a shell or capsule, with one end of the link connected with a surrounding metallic sleeve, threaded to adapt the plug to screw into and contact with the 10 conducting wall of a socket, while the other end of the link protrudes axially from or is connected with a central terminal upon the plug, in position to contact with another terminal within the socket.

20 In United States Letters Patent No. 628,180, issued in 1899 to Johnston, it has been proposed, in making plug fuses, to seat one end of a link wire in the eye of a pin inserted through the inner end of the shell 25 and having a head to limit its insertion and provide an external contact, the outer end of the shell being provided with a closure that is removable to admit of connecting up the other end of the link wire with the surrounding metallic sleeve through the medium of a rigid arm projecting therefrom. The present invention follows this general 30 plan of assembly, but employs a definitely formed link that is integral with the limiting and contacting head; and the inserted 35 end of the fuse link is supported by a spring arm constructed with a seat that receives and grips a specially formed head on the link, the position of the arm and length of 40 the link being such that hanging the link in its seat on the arm enforces considerable depression of the resilient arm and leaves the link and arm under considerable tension. There are several advantages accruing from 45 such an assembly of the parts. The link is integral with its central contact as required by the underwriters. The tension prevents vibration and maintains a good contact between the inner end of the link and the 50 spring arm and enforces quick separation of the parts of the link when fused. Another distinct and important function realized from the resiliency of the arm is that when the fuse acts, under an overload, the arm

snaps outward against or in such relation to 55 the end-closure as to serve as an indicator or tell-tale, the disk of the end closure being preferably transparent to facilitate observation. An important advantage arising from the use of integral heads of special form 60 upon links of predetermined length is that the heads enter the appropriately formed seats provided for them without the use of fastenings or manipulation of the material of the link; tensioning the spring arm and 65 setting it as an indicator is assured; the heads can be labeled or marked to indicate the capacity of the fuse link; and the introduction of links of inappropriate capacity is discouraged. Moreover, the capacity of 70 the link is always open to inspection, through its marking presented beneath the transparent end closure or window, and improper use of links of excessive capacity 75 would readily be detected. The conforming of the end opening of the shell and that portion of the fuse that seats therein not only safeguards against introduction of an improper link, but prevents rotation of the link 80 in the seat when the shell is screwed into the socket.

In the accompanying drawing in which one embodiment of the invention is shown by way of illustration:

Figure 1 is an axial section of the plug 85 fuse intact, the position of the hanger after "blowing" being shown in dotted lines;

Fig. 3 is a bottom plan view;

Fig. 4 is a section on the line 4-4 of 90 Fig. 1;

Figs. 5 and 6 are detail views of the link and the resilient support, respectively;

Fig. 7 shows a modified construction of 95 hanger.

A represents the body of the shell which is 100 of usual construction, being made of porcelain or other non-conducting material, and formed with threaded head *a* to receive the collar *B* for securing the transparent end closure disk *C*; also with reduced outer wall *a'* to receive the screw sleeve *D*, bore *a*² to receive and position the resilient arm *E* that engages the head *f* of link *F* and present the lower end of said arm for contact with the screw sleeve; also an end opening *a*³ 105 through which the link enters and in which the head *f'* on the outer end of the link seats. Spring arm *E* assumes an approximately

radial position in the shell, extending inwardly from its tang e that enters the longitudinal bore a^2 and extends beneath the sleeve D, and said arm terminates in the 5 seat e' that is slotted to admit the inner end of the link, and concaved to embrace the same head on said end and prevent the displacement of said head so long as the arm acts under its own elasticity.

10 Link F is of fixed length and has its heads f, f' that enter the seats a^3 and e' made integral therewith; head f being small enough to pass through the seat a^3 in entering the shell, and head f' being large enough to 15 limit the insertion, rest upon seat a^3 and provide the central contact G. Head f' is angular, and the opening of seat a^3 conforms thereto, so that the head cannot turn in its seat in screwing in the plug, and so that other 20 forms of link may not be readily introduced.

In assembling one of the new links with the shell, the end closure is removed, the link is passed through the opening of seat a^3 until arrested by the link head f' , the 25 resilient arm E is depressed until the reduced portion of the link, beneath the inner head f , can enter the slot, the arm is then released to permit it to embrace the head, and the end closure is replaced, when the 30 fuse will be ready for use. When the fuse melts under an overload of current, the arm moves under its inherent resiliency to instantly draw the parts asunder, thus keeping down arcing, and moves the inner head, or 35 its own free end, in such relation to the transparent end closure as to clearly indicate that the fuse has "blown." Even while the fuse remains intact the inner head is within plain view through the window of 40 the shell, and admits of inspection as to its capacity. To renew a fused link it is merely necessary to remove the shell from the socket, open up the end closure, clean out the fragments, and insert a new link in the 45 manner already described.

I claim:

1. A renewable link electric fuse, comprising a shell having at one end an opening through which to introduce the link, a link extending through said opening and into the 50 shell, and having one if its ends seated at said opening, and a resilient arm within the shell; said arm being constructed with a seat for the inner end of the link, and said inner end of the link being constructed to 55 conform to said seat and to be held in engagement therewith by the resiliency of the arm.

2. A renewable link electric fuse, comprising a shell having at one end a seat for the 60 link, and within it a resilient arm constructed to embrace the link, and a link having an integral head fashioned to conform to the embracing portion of the arm.

3. In a renewable link electric fuse, a 65 shell having a seat for one end of a fusible link, and having within it a resilient arm constructed with a seat for the other end of the link; the seat on the arm being concaved to embrace a head on the link, and being 70 slotted to admit the link when the arm is pressed past the head.

4. As a new article of manufacture, a renewable link for electric fuses, having at its 75 ends heads by which it is engaged in a fuse mounting, said heads being relatively large and small to permit the smaller head to pass and the larger head to arrest passage in introducing the link longitudinally into its mounting; an arm in the fuse mounting 80 constructed with a seat, said smaller head adapted to be received by and to conform to the seat on said arm.

The foregoing specification signed at Brooklyn, N. Y., this 5th day of November, 85 1917.

JOHN A. THAKE.
